UNITED STATES PATENT OFFICE

ROBERT TALBOT ROMINE, OF MOUNT CLEMENS, MICHIGAN

METHOD AND APPARATUS FOR HANDLING METAL

Application filed March 21, 1927, Serial No. 177,005. Renewed October 23, 1929.

This invention relates to a method and apparatus for handling metal, such as sheet metal, and for binding the metal sheets in packs, bundles or units to be placed in storage or upon the floor of a freight car or other carrier for shipment with the packs as individual units maintained intact at all times during transit or while being handled.

The present invention is a continuation in part of the invention shown and described in my Patent No. 1,650,540, patented Nov. 22, 1927.

My method and apparatus are especially adapted for use at mills, such as steel or aluminum mills, or other production sources wherein large quantities of metal such as sheet metal, strip or bar metal, are produced and wherein such metal is placed in storage for future delivery or is shipped in freight cars or other carriers to consumers in bundles or packs weighing, in many instances, as much as ten tons.

One of the objects of this invention is to provide an efficient and practicable method of handling metal, such as sheet metal, at the mills or elsewhere for the purpose of stacking the metal to form a pack of the desired size or weight, and binding the packs into units in such manner as to facilitate handling, storing or shipping of the sheet metal.

A further purpose of this invention is to provide a method wherein the metal, particularly in the case of sheet metal, may be first stacked flat after the final operation at the mill, may be bound or secured together into the proper size unit or pack, and thereafter transferred or conveyed to storage or to the freight car so that the sheets may be transported on edge.

40 A further object of the invention is to provide an improved apparatus for packing and transporting sheet, strip or bar metal on the floor of a freight car or carrier whereby shipment and handling of this material may be more efficiently carried out.

In the accompanying drawings, wherein like reference characters indicate similar parts in the several views, I have shown the 50 several steps of my method of handling metal

together with a preferred form of apparatus employed for carrying out the method.

In the drawings:

Fig. 1 is a side elevation of a loading table or buck adapted to receive the metal sheets 55 to be bound together in a pack or bundle.

Fig. 2 is an end elevation of the packing table or buck of Fig. 1 supporting a pile or pack of metal sheets stacked flatwise thereupon.

60 Figs. 3, 4 and 5 illustrate steps in the method of applying the binders to the pack of metal sheets.

Fig. 6 is a diagrammatic view illustrating a step in the method of handling a pack 65 preparatory to turning the sheets on edge.

Fig. 6^a is a view illustrating the step of turning the pack.

Fig. 7 is an enlarged perspective view of a lift truck platform showing the pallet in 70 position thereupon.

Fig. 8 is a diagrammatic view showing a bound pack being transferred from the packing table or buck to the lift truck platform.

Fig. 9 is a side elevation of a bound pack 75 of metal.

Figs. 10 and 11 are cross sections taken along the lines 10—10 and 11—11, respectively of Fig. 9.

Fig. 12 is a detail perspective view illustrating the manner in which the sections of a binder are adjustably connected together.

Fig. 13 is a detail perspective view illustrating the unassembled parts of one of the pressure devices.

85 Fig. 14 is a detail perspective view showing the spacer members of a binder.

Fig. 15 is a perspective view of the inside of a box car with a stack lifter supporting a bundle in elevated position.

90 Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of 95 100

description and not of limitation, and it is not intended to limit the invention beyond the terms of the several claims hereto appended or the requirements of the prior art.

5 The method of the present invention is illustrated in connection with the handling of sheet metal, and although the apparatus shown in the drawings is at present preferred by me for carrying out the invention it will 10 be apparent that other apparatus may be employed for practising the method. In general, the following steps are shown in the drawings by way of example: piling the metal sheets flatwise upon a packing table or 15 buck, applying binders to the pack while upon such packing table or buck, turning the pack to position the constituent parts thereof on edge, placing pallet members upon the lift platform of a lift truck, transferring the 20 bound pack to the lift truck platform and depositing it thereupon to be supported by the members of the pallet with the binder members preferably out of engagement with the lift platform, connecting the pallet and 25 the bound pack together, and thereafter transferring the pack and pallet from the lift platform to storage or to a position within a freight car or other carrier for shipment.

30 The packing table and sheet aligning device

In Fig. 1 I have shown certain improved apparatus for use in connection with the handling of metal sheets in accordance with my method. Preferably, I employ a packing table or buck A having legs A¹ and a flat 35 rectangular floor or supporting surface upon which are positioned a plurality of spaced transversely extending wood members A². I provide at one end of the table, a device B for 40 aligning the edges of the metal sheets of the pack P as it is being formed on the table A. The device includes a horizontal angle bar B¹ and a vertical angle bar B² rigidly connected together by means of a preferably triangularly shaped gusset plate B³, the several 45 members being rigidly connected together by means of rivets B⁴ to provide an integral structure. The horizontal angle B¹ is adapted to rest upon the floor surface and is 50 detachably connected thereto by means of a securing pin B⁵. The vertical angle B² serves as a stop for the constituent sheets of metal as they are placed in position flatwise upon the table A. To prevent the sheet aligning 55 device B from tilting as the sheets of metal are slid into position to be aligned one above the other, and likewise to prevent any accidental tipping or tilting of the table A, an angle 15 having a vertical flange 15^a and a horizontal flange 15^b is rigidly secured to the outer face of the angle B² by means of rivets or the like. The angle 15 is positioned upon the vertical angle B² in a manner permitting the engagement of its horizontal flange 15^b 65 with the under side of the table A. It will

be seen, therefore, that when the successive sheets are slid into position upon the table A, it will be impossible for the aligning device B to tilt relative to the table since the weight of the sheets is sufficient to prevent this. Any longitudinal or lateral movement of the device B relative to the floor and the table is prevented by the pin B⁵ which is inserted in a hole or slot provided in the horizontal angle B¹.

70 It may be found desirable to provide a pair of sheet aligning devices B rather than the single device shown in Fig. 1. In such case the transverse angle 15 is of a length to connect together the vertical angle bar B² of each of the spaced aligning devices B. It has been found in practice that for aligning relatively narrow sheets a single aligning device B is sufficient, such device being placed preferably at the center of the table end. Where 75 sheets of greater width are to be piled and bound into packs or bundles, it may prove desirable to employ two aligning devices of substantially the same construction as that shown at B in the drawings which devices, 80 as previously referred to, are interconnected by means of the transverse angle 15.

The binders

In Figs. 2 to 5 inclusive I have shown the 85 steps of binding the pile or pack of metal sheets P, employing, by way of illustration, a rigid binder of the type shown in my above 90 patent. This binder therefore comprises a plurality of sections C¹, C², C³ and C⁴, each 95 consisting of a pair of bent metal bars 16 and 100 17. The bars of each binder section are 105 arranged edgewise and in parallelism and connected together and maintained in spaced relation by means of bolts 19 which extend 110 through any of the horizontally aligned holes or apertures 16^a and 17^a provided in the bars 16 and 17, respectively, and through a tubular 115 spacer member or sleeve 18. After a bolt has been inserted through the aligned apertures and the sleeve 18, a nut 20 is threaded upon the exposed end of the bolt and tightened to draw the members 16 and 17 of the 120 binder section rigidly against the ends of the spacer sleeve 18. As will be seen in Fig. 12 the ends of the bars 16 and 17 of adjacent and 125 cooperating binder sections overlap in order to permit adjustment of the binders for packs of varying dimensions. The yoke portions of the binders are of substantially the same 130 construction as those shown and described in my patent above referred to.

In order to exert pressure upon the sides of the pack of metal sheets, I provide pressure 135 devices G. Each pressure device comprises a plate 25 bent at opposite ends to form a yoke adapted to embrace opposite sides of the parallel bars 16 and 17 of any one of the binder sections. The central web or portion 25^a of the yoke extends transversely across

the inner side of the bars 16 and 17. The web of each yoke is provided centrally thereof with a tapped hole 26 through which is threaded an adjusting screw 27. Interposed between the end of the adjusting screw 27 and the pack, is a metal thrust or bearing plate 28 provided with a depression or recess 29 positioned centrally thereof to receive and center the end of the adjusting screw 27. 10 Each plate 28 is preferably provided with multiple projecting portions on the outer face thereof (Fig. 11) forming a gripping surface for the plate.

Beneath the pack and upon the blocks A² 15 are located a pair of longitudinally extending spaced wood strips or bars E¹. At one vertical side of the pack, I also provide, for each binder, a vertically extending wood strip or bar F¹. The purpose of the strips or bars 20 E¹ and F¹ positioned at the under side and at one vertical side of the pack, respectively, is to provide cushioning means to prevent the binder sections, when tightened about the pack, from injuring or marring the metal 25 sheets, when pressure is applied to the pack to draw the binder members into contact and firmly hold the constituent sheets of the pack together as a unit.

In addition I provide, preferably, a pair 30 of longitudinally extending wood bars E, which bars are interposed between each of the bearing plates 28 and the top of the pack. At the vertical side of the pack opposite to the wood members F¹ are interposed between 35 the binders and the edges of the sheets vertical wood bars or members F.

The several wood strips or bars E, E¹, F and F¹ are all assembled during the operation of forming the pack. The purpose of 40 these wood members is two-fold. They provide protecting means for the metal sheets by maintaining the pressure devices and the sections of the binder out of direct contact with the pack, and likewise serve as longitudinally and transversely extending pack 45 engaging and supporting trusses.

Method of forming the pack

As previously referred to, I preferably employ a packing table or buck A and a sheet end aligning device B. The table A with its spaced wood blocks A² serves as a supporting surface for the sheets as they are piled thereupon by the workmen. To form a pack of 50 metal such as that shown at P in the drawings, a pair of the wood bars E¹ are placed upon the blocks A² and extend longitudinally of the table. The metal sheets of the pack are then slid into position upon the wood bars E¹ until their ends abut the vertical angle B² of the aligning device. Each successive 55 sheet is slid into position one above the other until a pile of the desired size and weight, and the requisite number of sheets, has been formed.

In Fig. 2 it will be seen that the binder sections C¹ and C² are interconnected beneath the pack P in the spaces provided between the wood blocks A². It will also be noted that the blocks A² are thicker than the width of 70 the binder sections, so that such sections may be inserted in the space between the wood bars E¹ and the top or supporting surface of the table A. The inner ends of the sections C¹ and C² are moved into cooperative overlapping relation until the binder sections assume the position in which they are shown in Fig. 3, or in other words, until they have been moved to proper relationship with respect to the particular bundle to be bound. 75 At this stage, the vertical wood strips or bars F may be interposed between the vertically extending portion of the binder section C² and the adjacent vertical edges of the sheets of the pack. When in this position 80 the bolts 19, spacing sleeves 18 and nuts 20 are applied to the overlapping end portions of the binder sections C¹ and C² to secure the sections together beneath the pack.

An additional pair of longitudinally extending spaced wood bars E are then placed in position upon the top of the pack of metal sheets and the pressure devices G for the top side of the pack may be placed in proper position thereupon. Thereafter the sections C³ 90 and C⁴ of the binder are brought into cooperative relation with the vertically extending portions of the binder sections C¹ and C² to cause the ends of the several sections to overlap as shown in Fig. 4. When in 95 this position it will be understood that the members 16 and 17 of the sections C³ and C⁴ are in engagement with the plate or yoke 25 of the pressure devices G at the top of the pack. The requisite additional bolts, sleeves 100 and nuts, 19, 18 and 20 respectively, are then placed in the horizontally aligned apertures 16^a and 17^a to secure the several sections of the binder together in cooperative relation 105 with respect to each other and to the pack of metal. The screws 27 of the top pressure devices G are now tightened to draw the horizontal portions of the binder sections C¹ and C² upwardly into engagement with the longitudinal wood bars E¹ beneath the pack, until 110 the binder assumes the position relative to the pack in which it is shown in Fig. 4.

The size of the pack having been taken into consideration and the binder sections adjusted accordingly until the parts are in the position in which they are shown in Fig. 4, it is then merely necessary to apply to the free vertical side of the pack, shown at the left in the figure, and between each binder and the pack a wood bar F substantially like the bar F¹. Additional pressure devices G are then inserted between the binder sections C³ and C⁴ and each wood bar F, and the screws 27 120 of the pressure devices manipulated to cause the thrust plates 28 to firmly engage the outer 125 outer 130

surface of the wood bar F. Additional pressure is then brought to bear upon the vertical side of the pack, at the left in Fig. 5, to force the sheets evenly against the bars F at the opposite side of the pack and align the edges thereof. This application of pressure at the left hand vertical side of the pack causes the binder sections at the opposite vertical side to move into engagement with the wood strip or bar F¹ and firmly bind the latter between the binder sections and the right hand vertical side of the pack, and to cause the edges of the sheets to bite into the soft wood bars F and F¹.

After the edges of the sheets have been aligned properly against the vertical wood members F¹, additional pressure is applied to the longitudinally extending wood bars E at the top of the pack through the medium of the pressure devices G at the top of the pack. By tightening the screw 27 of each of the pressure devices, it will be understood that the bottom horizontal portions of the binder sections C¹ and C² which underlie the pack of metal, are further drawn upwardly into contact and engagement with the longitudinal wood bars E¹ and serve to clamp the bars against the under side or face of the pack.

From the foregoing it will be understood that by preliminarily tightening the pressure devices G at the top of the pack sufficiently, the binder sections are drawn upwardly to bring the bottom portions of the binder lightly into engagement with the wood bars E¹ at the bottom of the pack. Thereupon, by tightening the pressure devices G at the left side of the pack in Fig. 5, the vertically extending binder portions C² and C⁴ will be clamped against the wood bars F¹ at the right hand side of the pack, thereby aligning the edges of the sheets. After the binder has been drawn into the position in which it is shown in Fig. 5, final pressure is exerted upon the top of the pack through the medium of the pressure devices G positioned above the pack. The foregoing steps of the method may be readily and quickly accomplished, whereby the constituent sheets of the pack are bound together into a unit with the sheets positioned flatwise.

Handling the bound pack

After the pack has been bound as shown in Fig. 5, it may be turned approximately ninety degrees by simply rolling the pack over by means of suitable power apparatus, such for example as a crane, the hoist hooks of which are connected at the side of the pack to one of the binder bolts 19 and spacer sleeves 18 of each binder.

Referring to Fig. 5 it will be noted that the pack P is supported directly upon the wood blocks A² and the weight of the pack is supported independently of the binders. In order to roll or turn the pack over on its

binders it is necessary to transfer the weight of the pack from the blocks A² to the binders, so that the pack will turn or roll over upon the curved corner portions X of the binders. The hoist hooks 40^a of a suitable hoisting mechanism, such as an overhead crane, are connected at each side of the pack to each of the binders and the pack is lifted from the table A by means of the hoist mechanism and deposited on the floor Y of the plant, in the manner shown in Fig. 6. The crane is preferably attached to the pack at four points at opposite sides of the pack, which enables the weight of the pack to be distributed and has the advantage of preventing swing or tilting movement of the pack, this being especially important where units weighting as much as ten tons are being handled.

When the pack has been deposited upon the floor, a pair of the hoist hooks 40^a is disconnected at one side of the pack, such as the right hand side in Fig. 6^a and thereupon the crane is operated and traversed in such manner as to lift one side of the pack and roll it over as shown in the drawing. After the pack has been turned so that the constituent parts or sheets thereof rest on edge, as shown in Fig. 6^a, the crane hooks may be connected again to the opposite sides of the pack through the medium of the binder bolts 19 and spacer sleeves 18 of the binders, and the pack may be lifted onto a suitable conveying medium or may be transferred by the crane directly to storage. At some plants the packs, after being turned with the sheets or strips on edge, are transferred directly to a lift truck platform L and carried to the freight car. In such cases the wood supporting members for the pack are placed on the floor of the car and the pack transferred from the truck to the wood pallet members by means of a stack lifter V, such as shown in Fig. 15.

In accordance with the present invention, however, I have provided a way in which the supporting pallet I may be handled with the pack as a unit, thereby effecting a considerable saving in labor and time.

The wood pallet upon which the pack is supported on the car floor may be built up on the lift truck platform L by the workman before the pack is lifted from the floor onto the truck platform. This pallet may comprise a pair of parallel longitudinal wood members 30 which are first laid on the truck platform. A series of transverse wood members 31 are then laid across the members 30 in spaced relation from one another. The pack is then lifted as shown in Fig. 8 by means of the crane and deposited on the members 30 and 31. As the pack is lowered onto the cross members 31 the workman adjusts these members into the desired positions with relation to the pack so that the binders will lie in the spaces between the end pairs of cross mem-

bers 31, as shown in Fig. 8. The transverse members 31 in the present instance are of sufficient thickness to maintain the binders C out of contact with the longitudinal members 30 of the pallet and the floor of the freight car, yet permitting the lower edges of the sheets of the pack P to rest upon the transverse members 31 and bite into the top surfaces thereof to frictionally resist longitudinal movement of the pack as a unit relative to the transverse supporting members 31 during transit.

After the pack has been placed on the pallet members 30 and 31 the latter may be secured together in any suitable manner, such as by nails N, see Fig. 9.

A pair of longitudinally extending wood members or bars 32 are positioned at opposite longitudinal sides of the pack upon the transverse wood blocks 31, the members 32 serving to maintain the pack against lateral or sidewise movement or displacement relative to the pallet members 30 and 31. The longitudinal wood members 32 are then secured to the transverse members by means of nails or the like 31^a. It will be understood that the inner vertical face or side of each member 32 is in abutting relation to the side of the pack of metal. In order to connect the pack and pallet together as a unit, a pair of angle plates or brackets 33 may be positioned adjacent opposed ends of the members 32, and secured thereto and to the wood bars E and E¹ by means of nails or the like 33^a (Fig. 9).

The pallet members 30 and 31 are thus connected with the pack to form a single unit through the medium of bars 32 and the devices 33 at each side of the pack. The bars 32 in addition provide means for resisting sidewise displacement of the pack relatively to the pallet during transit.

The bound pack and pallet, as a complete unit, are then propelled upon the lift platform L of the truck to any desired point, either to a storage warehouse or directly into a freight car. The unit is then lifted from the platform and placed upon the storage warehouse floor or upon the car floor as desired. In the first instance, an ordinary overhead crane may be employed to effect the transfer of the unit, whereas in the latter case, I preferably employ a stack lifter (Fig. 15) of the character shown and described in my co-pending application Serial No. 133,374, filed September 3, 1926.

The truck T may be propelled directly into the car with the pack on the lift platform L straddled at opposite sides by the legs of the stack lifter. The hoist mechanism of the lifter is then connected to the binders at opposite sides of the pack, whereupon the pack is lifted, the truck platform backed out from beneath the pack, and the

pack and pallet deposited on the car floor as a unit.

From the foregoing it will be seen that the sheet metal may be bound for transportation on the car floor by supporting and maintaining it as a unit on pallet or skid members permitting the entire unit to shift or float on the car floor when the car is subjected to shocks or blows in transit.

What I claim is:

1. The herein described method of preparing metal such as sheet metal for shipment on a carrier, which consists in piling the constituent sheets of the pack flatwise on a support, placing binders about the pack, applying pressure through the medium of said binders, and turning the pack to position the sheets on edge.

2. The herein described method of packing metal such as sheet metal with the constituent sheets of a pack piled flatwise, which consists in placing binders about the pack, applying pressure to certain sides of the pack through the medium of said binders, turning the pack to dispose the sheets on edge, and supporting the pack on a pallet on a car floor.

3. The herein described method of loading metal for shipment, which consists in piling or stacking the metal on a support, placing binders to encircle the pack, applying pressure at the top and at one vertical side of the pack through the medium of said binders, and supporting the bound pack on a carrier floor with the pack turned ninety degrees.

4. The herein described method of loading metal for shipment, which consists in stacking the metal such as sheet metal flatwise in a pack, placing binders at the top, bottom and sides of the pack, securing the binders to the pack by applying pressure successively at two sides of the pack in directions at right angles to each other, and turning the pack ninety degrees for shipment on the floor of a carrier.

5. The herein described method of loading metal for shipment, which consists in stacking sheet metal flatwise to form a pack, binding the pack by applying pressure at the top and at one vertical side of the pack, and turning the pack to dispose the constituent sheets on edge.

6. The herein described method of loading metal such as sheet strip or bar metal for shipment, which consists in piling or stacking the metal to form a pack, placing binders at the top, bottom and sides of the pack, securing the binders to the pack by applying pressure at the top of the pack and at one vertical side thereof, then turning the pack ninety degrees to dispose the binders opposite said vertical side beneath the bundle.

7. The herein described method of handling metal, such as metal sheets, which consists in stacking the metal flatwise to form pack or bundle, binding the pack into a unit,

and turning the pack to dispose the constituent parts on edge.

8. In an apparatus of the class described, the combination of a pair of binders adapted to encircle and embrace a pack of metal sheets, pressure devices carried by said binders and adapted to apply pressure to two sides of the pack in directions at right angles to each other, and pallet members for supporting the pack on a car floor and means for detachably connecting the pallet members to the pack.

9. In an apparatus of the class described, the combination of a plurality of adjustable binders adapted to encircle and embrace a pack of metal sheets, and means adapted to be positioned between said binders and said pack for exerting pressure upon one vertical side and the top of said pack only when the pack is supported with the sheets on edge.

10. In an apparatus of the class described, the combination of an adjustable binder to embrace a pack of metal sheets, and pressure devices detachably connected with said binder and adjustable relatively thereto for exerting pressure upon two sides only of the pack.

11. In an apparatus of the class described, the combination of binding means adapted to embrace a pack of metal sheets, and a pallet disposed beneath the pack for supporting the same free of its binding means, said pallet including a pair of longitudinal members, transverse members detachably connected with said members and mounted thereupon, and means at opposite sides of the pack detachably connected therewith and with the transverse members for restricting the lateral movement of the pack relative to the pallet.

12. In an apparatus of the class described, the combination of binders adapted to embrace a pack of metal, and a pallet disposed beneath the pack for supporting the same free of its binders, said pallet including a pair of parallel longitudinal members, spaced transverse members mounted upon said members for supporting the pack with the binders positioned within the spaces between said transverse members, and wood members at opposite sides of the pack and connected with said pallet for restricting lateral movement of the pack relative to said pallet.

13. The combination of members mounted on a car floor for supporting a pack of sheet metal with the sheets on edge in engagement with said members, and longitudinally extending members engaging opposite sides of the pack for maintaining the pack on said members against lateral displacement.

14. The combination of transverse wood members mounted on a car floor for supporting a pack of sheet metal with the sheets on edge in engagement with said members and extending longitudinally of the car, and means connecting said members together and

engaging opposite sides of the pack for maintaining the pack on said members against lateral displacement.

15. An apparatus for packing sheet metal or the like on the floor of a freight car, comprising wood members extending longitudinally of the car upon the floor thereof, and binding means for maintaining the pack together as a unit on said members and connected thereto.

16. An apparatus for packing sheet metal or the like on the floor of a freight car, comprising wood members extending longitudinally of the car upon the floor thereof, and binding means for maintaining the pack together as a unit on said members and held thereto against relative movement, said wood members having the ends thereof tapered.

17. An apparatus of the class described, comprising members extending beneath a pack of metal for supporting the pack in such manner upon the car floor as to permit floating movement of the pack and members when the car is subjected to blows or shocks, means for connecting said members together, and binding means for maintaining the pack together as a unit and connected with said members.

18. The herein-described method of binding a pack, such as sheet strip or bar metal, for shipment on the floor of a carrier, which consists in placing binding means about a pack, interposing wood material between the binding means and pack at a pair of opposite sides thereof, and applying inward pressure against the pack at one of said sides only to draw the binding means against the wood material and pack at the opposite side of the pack.

19. The herein-described method of binding a pack such as sheet strip or bar metal, for shipment on the floor of a carrier, which consists in placing binding means about the pack, interposing wood material between the binding means and pack at a pair of opposite sides thereof, and exerting pressure on the binding means and pack at one of said sides only to force the binding means at the opposite side against said material and pack.

20. The herein-described method of packing metal such as sheet metal for shipment on the floor of a carrier, which consists in binding the pack with the constituent parts arranged in a pile and applying pressure to two sides of the pack in directions at right angles to each other, and thereafter turning the pack on one of said sides for shipment on the carrier floor.

In testimony whereof I affix my signature.
ROBERT TALBOT ROMINE.
